(57) **CLAIM**

The ornamental design for a record player, as shown and described.

DESCRIPTION

FIG. 1 is a front, left and top perspective view of a record player, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is an enlarged view of portion 8 identified in FIG. 1; and,

FIG. 9 is an enlarged view of portion 9 identified in FIG. 1. The dashed broken lines in the drawings depict portions of the record player that form no part of the claimed design. The ovoidal dashed broken lines in FIGS. 1, 8, and 9 depict the boundaries of the enlarged view and form no part of the claimed design.

1 Claim, 9 Drawing Sheets
